AMPLIFYING SYSTEM

Anton Leendert Timmer, Eindhoven, Netherlands, assignor to Radio Corporation of America, a Corporation of Delaware

Application October 3, 1929, Serial No. 396,991,
and in the Netherlands October 4, 1928

6 Claims. (Cl. 179—171)

My present invention relates to receivers, and, more particularly, to circuit arrangements for amplifying electrical oscillations.

It has been proposed to provide a circuit arrangement for amplifying electric oscillations by means of two thermionic devices which are so connected that the output circuit of the former is common to the grid circuit of the second device, this latter device working, consequently, with a positive mean grid bias that is equal to the product of the current and the resistance of the path of discharge between the grid and the cathode of the last mentioned device.

15 Accordingly, in this invention an especially simple and also efficient control of the degree of amplification is assured by the grid and the cathode of the second device being connected with the interposition of a variable resistance.

20 Thus, indeed, the highly desirable condition is secured that on a decrease of the amplification (by reduction of the resistance) the positive grid bias, and consequently the energy expenditure in the second device, falls likewise.

25 The novel features which I believe to be characteristic of my invention are set forth in particularity in the appended claims, the invention itself, however, as to both its organization and method of operation will best be understood by 30 reference to the following description taken in connection with the drawing in which I have indicated diagrammatically one circuit organization whereby my invention may be carried into effect.

35 One circuit arrangement according to the invention is diagrammatically shown on the accompanying drawing.

The oscillations to be amplified (for example audio frequency currents) are led into the primary of an input transformer T_1 , the secondary of which is connected between the grid and the cathode of a triode I. The anode of I is connected to the positive pole of a battery B, and the cathode of I is connected to the grid of a triode II which serves as the final amplifier. The anode of II is connected through the primary of an output transformer T_2 to the positive pole of B and the cathode of II is connected to the negative pole of B.

40 In conclusion, a variable resistance R is connected in parallel to the path of discharge between the grid and the cathode of the valve II, and enables the degree of amplification of the 45 device to be varied within certain limits. The output current of I is, indeed, distributed about

the resistance R and the path of discharge (grid cathode) of valve II so that when R is reduced the grid current of II, and consequently the value of the positive grid bias of this valve, decreases. This has the desired effect that the 60 anode current and consequently the energy expenditure (the anode dissipation) in the valve II diminishes.

While I have indicated and described a system for carrying my invention into effect, it will 65 be apparent to one skilled in the art that my invention is by no means limited to the particular organization shown and described, but that many modifications in the circuit arrangements, as well as in the apparatus employed, may be 70 made without departing from the scope of my invention as set forth in the appended claims.

What I claim is:

1. In an amplifier circuit a plurality of space discharge devices having cathode, anode and 75 control electrodes, a source of potential, the cathode of one of said devices being directly connected to the control electrode of a following device, means for operating said control electrode at a positive potential with respect to the 80 cathode of said last named device, a variable impedance connected between said control electrode and the low potential side of said source and means for connecting the anodes of both of said devices to a common point of high 85 potential of said source.

2. In an amplification system comprising in effect a pair of thermionic devices connected so that the output circuit of one includes the grid-cathode path of the other, means for operating said latter device at a positive mean grid bias with respect to its cathode, and an impedance connected across said grid-cathode path.

3. In an amplification system comprising in effect a pair of thermionic devices connected so that the output circuit of one includes the grid-cathode path of the other, means for operating said latter device at a positive mean grid bias with respect to its cathode, and a resistance connected across said grid-cathode path.

4. In an amplification system, a pair of thermionic devices connected so that the output circuit of one is common to the grid-cathode circuit of the other, means for operating the second device at a positive mean grid bias with 105 respect to its cathode, and means for varying said positive mean grid bias for controlling the amplification characteristics of the system.

5. In an amplification system in which two 110 thermionic devices are connected so that the

output circuit of one is common to the grid circuit of the other, means for operating said other device with a positive mean grid bias which is substantially equal to the product of the current 5 and the resistance of the path of discharge between the grid and cathode of the last mentioned device, and means for varying the current flowing across said path comprising a variable impedance path in shunt relation to the 10 said path for determining the amplification characteristics of the second device.

6. In an amplification system comprising, in effect, a pair of cascaded space discharge devices, each of said devices including anode, cathode 15 and grid electrodes, a connection between the grid and cathode of the first device including means for connecting thereto a source of energy to be amplified, a source of space current for

both of said devices having positive and negative sides, a direct connection between the anode of the first of said devices and the positive side of said source, means for operating the second device at a positive mean grid bias potential with respect to its cathode comprising a direct connection between the cathode of the first device and the grid electrode of the second device, and a connection from the cathode of the second device to the negative side of the source whereby the grid cathode path of the second device is, in effect, included in the output circuit of the first device, an impedance path shunted across the grid-cathode path of said second device, and a load coupling impedance connected between the anode of the second device and the positive side of said source.
